UNITED STATES PATENT OFFICE

FRANK FRYE, OF DETROIT, MICHIGAN

MEANS FOR SUCCESSIVELY EXHIBITING GROUPS OF SIGNS

Application filed May 4, 1927. Serial No. 188,708.

This invention relates to means for automatically exhibiting in proper sequence the several signs composing a desired group of indicia, as advertisements or announcements, and for selecting the desired one of a series of such groups.

In the illustrated embodiment, I have shown, as an example, a group of signs, each bearing the name of a street or streets, arranged so that they will automatically be exhibited in proper sequence to project on a suitable screen the names of the streets about to be passed by a street car or other vehicle. Then, as a street car may be used on any one of a number of routes, means are provided for selecting any one of a series of groups bearing in rotation the names of the streets passed on the desired route. One of the objects of my invention is the provision of such means for selecting a certain one of a series of groups of signals at the will of the operator, and thereafter feeding the individual signals of the group in proper sequence at predetermined intervals.

Another object of this invention is the provision of means for automatically feeding the several signals of a group for projection on the screen.

A further object of my invention is the arrangement of such feeding means whereby the several signals of a group may be fed alternately in reverse order, or may be continuously rotated in the same order, at the will of the operator.

A further object of this invention is the provision of means for retaining a signal change contact until the change is completed regardless of how short the time interval of the original contact energizing the mechanism for such change.

A further object of my invention is the arrangement of means for interrupting the circuit for illuminating the projector during a signal change.

The above and other objects will be apparent from the following description, taken in connection with the accompanying drawings, wherein is illustrated a preferred embodiment of my invention.

In the drawings, Figure 1 is a plan view

of the feeding and projecting mechanism for successively exhibiting the signs of any group.

Figure 2 is a front elevation thereof.

Figure 3 is an enlarged detail plan view of the forward extremity of my improved feeding mechanism, arranged to feed the signs in one direction, the projecting mechanism being omitted.

Figure 4 is a similar view of the feeding mechanism arranged to feed the signs in the reverse direction.

Figure 5 is an enlarged detail side elevation of one corner of the guide frame for the signal slides and mechanism for shifting one signal at a time before the projector.

Figure 6 is a detail plan view of one side portion of the adjustable frame for groups of signals.

Figure 7 is a detail cross section taken substantially on the lines 7—7 of Figure 6.

Figure 8 is a detail section taken substantially on the line 8—8 of Figure 6, but showing only one of the telescoping members.

Figure 9 is a detail section taken substantially on the line 9—9 of Figure 6, but showing only the other of the telescoping members.

Figure 10 is a detail figure taken substantially on the line 10—10 of Figure 6.

Figure 11 is a detail plan view of the latch utilized in advancing the signals before the projector, and

Figure 12 is a diagrammatic view of the electrical mechanism utilized for selecting one of a series of groups of signals and for electrically controlling the successive changes of signals before the projector.

Referring now to the drawings, the numeral 2 designates a frame for supporting the exhibiting mechanism and for supporting and guiding the several signals to be exhibited. As herein shown, the frame is composed of side angle irons 3 telescopically mounted for adjustment of the length of the frame, and with cross bars 4 connecting the angle irons. Suitably supported upon the frame is a projecting mechanism arranged to project an image from the several signals herein shown as stereopticon slides 5 on to a screen 6 by means of a lamp 7, reflector 8,

condenser lenses 9, and projector lenses 10. The several slides 5 are stored on either side of the projecting mechanism and are successively brought between the condenser lenses 5 9 and projector lenses 10 by the motor driven mechanism hereinafter described.

The feeding mechanism herein shown for successively advancing the slides 5 into position for projection comprises a motor 11 10 adapted to be energized at predetermined intervals, as hereinafter described, and driving a worm pinion 12 meshing with a worm gear 13 mounted on a stub shaft 14 also bearing a pinion 15 meshing with a gear 16 affixed to 15 the telescopic shaft 17. This reduction gearing permits the rapid rotation of the motor with a comparatively slow movement of the slides. Eccentrically mounted upon the gear 16 is a pin 18 on which is pivotally mounted 20 one extremity of a link 19, the other extremity of which is pivotally connected with a post 20 fixed upon a traveller bar 21 at the opposite extremities of which are pivotally mounted a pair of latches 22 (note Figures 25 3 and 11). The rotation of the gear 16 will serve to reciprocate the traveller bar 21, and this reciprocating movement is utilized to move the foremost slide 5 from the aligned 30 slides at one side of the projector mechanism to in front of the condenser lenses 9 on one revolution. Then the traveller bar returns to pick up the next slide of the series (which has been forced into the foremost position) and on the next revolution of the gear 35 16 this latter slide is then moved into position before the condenser lenses 9, forcing the first mentioned slide away from in front of the condenser lenses and into alignment with the slides on the opposite side of the 40 projecting mechanism. To insure correct alignment of the slides on both sides of the projecting mechanism, I provide shoes 23a and 23b at the ends of the right and left hand stacks of slides and position them for 45 both maintaining the bunched or stacked relation of the several slides and for guiding the slide moving from in front of the condenser lenses into alignment with the other slides in the opposite stack. As best shown 50 in Figs. 3 and 4, one of the shoes, as 23b in Fig. 4, is set at a distance in front of the other shoe, as 23a, equal to the thickness of one of the slides 5. This places the inner shoe 23a so that it aids in bunching the 55 stacked slides on the right side so that they are in position for receiving another slide, which is slid into correct position first by the beveled toe of the shoe and lastly by the substantially rigid heel portion of the shoe. 60 The shoes 23a, 23b are pivotally mounted upon pins 24 extending through apertures in a bracket 25 on the shoe, providing a pivot for the shoe remote from the toe portion. A spring pressure is also provided to force the 65 toe portion of the shoes toward the stacked

slides as far as permitted by stop pins 26 or by the position of the slide then in contact with the toe portion of the shoe. As herein shown, a guide pin 27 secured upon the toe portion of the shoe loosely fits within an aperture 28 in a bracket 29 fastened upon the frame 2, and a coiled spring 30 is arranged between the toe portion of the shoe and the adjacent face of the bracket 29, surrounding the pin 27. Each bracket 25 on the heel portion of the shoe is connected by its pivot pin 24 with one extremity of a link 31, the opposite extremity of which is pivotally mounted upon the bracket 29. By rocking the link 31 until it is at substantially right angles to the heel portion of the shoe, as shown at the right in Fig. 4, the heel portion is moved inwardly a distance differing from the position assumed by the heel portion when the link 31 is obliquely arranged relatively to the heel portion, as shown at the left in Figure 4, by the thickness of a slide 5.

The pivot pins 24 joining the links 31 with the brackets 25 of the shoes at each end of the frame 2 are preferably connected together, as by means of a cross bar 32, so that when the cross bar 32 is moved laterally both of the links 31 will be moved to their opposite extreme positions, thereby moving inwardly the shoe, as 23b, that had previously been utilized only for compressing its stack of slides, while the shoe, as 23a, previously used for guiding oncoming slides, is moved outwardly to a position where it is out of the path of the lateral travel of the slides. This constitutes a reversing mechanism, whereby the slides previously fed from, say, the left hand stack to the right hand stack, as in Figure 4, will now be fed from the right hand stack to the left hand stack of slides, as shown 100 in Figure 3. In this reversed position, the latch 22 at the opposite extremity of the traveller bar 21 will be utilized to engage the side edge of the foremost slide of the adjacent stack and move it to a position before the condenser lenses 9 while the latch 22, previously used for advancing the slides from the other stack, will now be idle, and will remain so until the reversing mechanism is again moved to feed the slides from the 105 stacks as at first described.

The mechanism above described in connection with the forward extremity of the stacks of slides is duplicated at the rear extremity thereof, only the positions of the shoes 23a and 23b are reversed to enable the automatic movement of the rearmost slides from one stack to another simultaneously with the transfer of the foremost slides from one stack to the other to exhibit them. In other words, the number of slides in each stack is always constant, the foremost slide of one stack being moved to the other stack while the rearmost slide of the second stack is moved over to the rear of the first stack. 120 125 130

Accordingly, there is substantially uniform compression upon the end slides of the stacks, and light springs 30 will serve to supply the requisite pressure to insure uniform movement of the slides. It is to be noted that the face of the shoes 23 adjacent the slides are cut away except at their upper and lower edges to supply means for engaging only the upper and lower portions of the several slides, and thereby preserving the film or other transparent or translucent central portions of the slides carrying the legends to be exhibited.

To enable the introduction of additional slides, to the stacks, or to reduce the number of slides, I preferably provide an adjustable frame substantially as shown herein. By forming the side members 3 of the frame of telescoping angle irons, one of which carries a pair of spaced guide bars 34 and the other of which carries a central guide bar 35 (note Figures 6-10) I am enabled to secure ready adjustment of the frame members, and any desired adjustment can be maintained by securing tie-bolts 36 between the cross bars 4 at the ends of the frame. The shaft 17 connecting the gear 16 with the crank member 16a for operating the traveller bar at the rear extremity of the slide stacks should also be a telescoping one so that the simultaneous transfer of the endmost slides will be made at each end of the stack regardless of the number of slides in each stack.

From the above it will be apparent that I can move the foremost slide from either the left or right hand stack to a position before the condenser lenses 9 of the projector mechanism to thereby project its legend onto the screen 6, then move the following slide in position to be projected, meanwhile forcing the slide just projected on to the opposite stack. Simultaneously the rearmost slide of the second stack is similarly moved on to the rear of the first stack to maintain the number of slides in each stack constant. These slides may bear legends such as the names of streets, or advertisements, warnings, announcements, etc. Supposing for example, that the slides illustrated in Figure 1 bear legends showing the names of streets in proper sequence on several street car routes in a large city. With the frame and slides properly mounted on the street car, the slides bearing the names of the streets on any desired route will be successively brought into position as the car travels over its route in one direction. Then, the reversing mechanism is thrown to alter the positions of the shoes 23a and 23b, whereupon the same slides will be moved into position for projection in reverse order. When, however, it is desired to move that street car on to a different route, it is necessary to preliminarily position the slides so that the first slide of the new route is at the foremost end of a stack of slides. One way of accomplishing this is diagram-

matically illustrated in Figure 12, wherein the manual rotation of the route sign 37 is utilized for positioning the initial slide of the desired route. On the route sign 37 is positioned a plurality of metallic bridge strips 38, 39, adapted to contact adjacent pairs of contact fingers 40 and 41. Bridge strips 38 may be considered as starting strips, i. e. they energize the motor 11 to move the slides from one stack to the other until the desired initial slide of the new route is properly positioned. This is determined by the bridge strips 39, which may be termed stop strips, in combination with upwardly projecting metallic contact members 42 carried upon the initial slides 5 of each route. Accordingly as the motor is set in motion through the starting strip 38, it continues to move slides from one stack to the other until such time as both the bridge strip 39, which is manually set by properly positioning the route sign 37, and the upwardly projecting contact 42 of the proper slide are in series with each other, as shown in Figure 12. The motor is then stopped, and the initial slide on the new route remains at the foremost position of the desired stack until the motor is again set in motion, as by closing of its circuit through engagement of a moving contact 43 mounted on the street car adjacent its trolley pole with a stationary contact 44 carried adjacent the trolley wire 45 at, say, a half block ahead of the street whose name is carried by the initial slide of that route. When the moving contact 43 engages the stationary contact 44, the circuit is closed through the relay magnet B to lift the double arm switch 46, whereupon the current from the trolley wire may pass through the wire 47, resistance 48, lower arm of the switch 46, and wire 49 into the motor 11, emerging through wire 50 into a suitable ground. The rotation of the motor 11 turns the gear 16 until its radially projecting contact 16b engages the stationary leaf spring contact 51, which is connected through the lower arm of the double arm switch 52 of the relay magnet A whenever such arm is in its lowered position. The lower switch arm of the switch 52 is also connected by the wire 53 with one side of the relay magnet B, the other side of which is connected with a suitable ground. Also the opposite side of the gear 16 is grounded, as by the wire 54. Accordingly when the radially projecting contact 16b engages the leaf spring contact 51, both sides of the relay magnet B are connected with the ground, so that such magnet becomes de-energized, permitting its double arm switch 46 to fall to its lowered position, breaking the circuit to the motor. The momentum of the gear 16, however, will carry the radially projecting contact 16a out of contact with the leaf spring contact 51. From the above it will be apparent that the motor will be

70

105

110

115

120

125

130

energized whenever a stationary contact 44 is engaged by the movable contact 43 carried by the street car, and even though such contact be momentary, it will be sufficient to lift the double arm switch 46 to permit the continued energization of the motor until a substantially full revolution has been made by the gear 16. Then the circuit to the motor is automatically broken. By placing the stationary contacts 44 a suitable distance in advance of the reaching of each street, the motor will be energized in time to project the name of the street on to the screen 6 as an announcement to the passengers.

15 Means are also provided for extinguishing the lamp 7 during the operation of the motor 11. One side of the lamp 7 is connected with a suitable ground, as by wire 55, while the other side of the lamp is connected, 20 as by the wire 56, with the lower arm of the double switch arm 46 when such arm is in its normal or lowered position. In other words, the current to the lamp passes from the wire 47 through the lower arm of the 25 switch 46, and wire 56, to the lamp at all times except when the switch 46 is raised by the energization of relay magnet B to energize the motor 11. Accordingly the light 7 is extinguished while a slide is being moved 30 into position for projection, then after the slide has been suitably positioned the relay magnet B is automatically deenergized, permitting the switch arm 46 to fall and restore the circuit for illuminating the lamp 7.

35 To enable the rapid transfer of slides from one stack to another, when it is desired to change the car from one route to another, I preferably provide a relay magnet A controlling the double arm switch 52, whereby 40 the lower arm of such switch 52 is moved out of engagement with the leaf spring contact 51 to prevent deenergization of the motor each time the spur 16B engages contact 51. The energization of the magnet A is 45 controlled by the starting bridge contact 58 passing between the wire 47A, joining wire 47 with contact 47B and one of the contacts 40, which is joined, as by the wire 57 with one side of the magnet A, the other 50 side of such magnet being grounded as by the wire 58. The energization of the magnet A serves to lift the double arm switch 52, breaking the contact with the leaf spring 55 51 and permitting the passage of current through wire 57 to wire 53 to energize the magnet B and lift its double arm switch 46, whereupon the current can flow directly through wire 47, switch 46, and wire 49, to the motor 11. The motor continues to rotate 60 without having its current broken by engagement of its spur contact 16B with the leaf spring contact 51 until the proper stop bridge contact 59 and upwardly projecting contact 42 on the proper slide 5 has been 65 reached, whereupon the current is grounded

through the slide, shorting the relay magnet A, and thereby deenergizing the relay magnet B by permitting the lower arm of the switch 52 to again engage the leaf spring contact 51. Then when the spur contact 16B 70 on the gear 16 again reaches the spring contact 51, both sides of the magnet B are grounded, as herein above described. The new route slides are now in position for successive projection in accordance with the 75 intermittent energization of the motor 11 by engagement with the movable contact 43 on the trolley with the suitably positioned stationary contacts 44 along the route travelled by the car.

80 While it will be apparent that the illustrated embodiments of my invention herein disclosed are well calculated to adequately fulfill the objects and advantages primarily stated, it is to be understood that the invention is susceptible to variation, modification and change within the spirit and scope of the subjoined claims.

Having described my invention, I claim:

1. Means for successively exhibiting a plurality of signs including a frame, a projecting mechanism arranged substantially centrally of the frame, a stack of signs arranged on each side of the projecting mechanism, means for moving the foremost sign from either stack into position for projection and then onto the other stack, including a traveller bar mounted to reciprocate across the frame and having a pair of latches at its opposite ends arranged whereby one of the latches will engage the foremost sign of one of said stacks, means for reciprocating the traveller bar whenever desired, means for compressing the signs in the stacks so that the foremost sign on one stack extends forwardly beyond the foremost sign of the other stack and in to the path of movement of one of the latches of the traveller bar, means for transferring the rearmost sign from the second stack to the first stack simultaneously 100 with the transfer of the foremost sign of the first stack onto the second stack, and means for reversing the positions of the foremost signs of the stacks to permit the signs from the second stack to be transferred onto the 105 first stack through engagement with the other latch of the traveller bar.

2. In a device of the character described, a frame, projecting mechanism arranged substantially centrally of the frame, a pair of stacks of signs arranged at the sides of the projecting mechanism, means for simultaneously transferring the foremost sign of one stack and the rearmost sign of the other stack onto the opposite stacks to maintain 120 constant the number of signs in each stack, the path of movement of the transferred signs at one end of the stacks being past the projecting mechanism, including reciprocable traveller bars adjacent the opposite 125 130

ends of the stacks and having latches at their opposite extremities, means for simultaneously reciprocating the traveller bars, means for arranging the sign stacks whereby the foremost sign of one stack and the rearmost sign of the other stack will be within the path of movement of a latch on the adjacent traveller bar, and means for reversing the positions of the sign stacks to bring the foremost sign of the second stack and the rearmost sign of the first stack into the path of movement of the opposite latches on the respective traveller bars.

3. In a device of the character described, a frame, projecting mechanism arranged substantially centrally of the frame, a pair of stacks of signs arranged at the sides of the projecting mechanism, means for simultaneously transferring the foremost sign of one stack and the rearmost sign of the other stack onto the opposite stacks to maintain constant the number of signs in each stack, the path of movement of the transferred signs at one end of the stacks being past the projecting mechanism, pivoted shoes arranged to compress the signs in each stack and to guide the transferred signs in their movement from one stack to the other, and springs urging the shoes into substantially constant engagement with the stacks.

4. In a device of the character described, a frame, projecting mechanism arranged substantially centrally of the frame, a pair of stacks of signs arranged at the sides of the projecting mechanism, means for simultaneously transferring the foremost sign of one stack and the rearmost sign of the other stack onto the opposite stacks to maintain constant the number of signs in each stack, the path of movement of the transferred signs at one end of the stacks being past the projecting mechanism, including reciprocable traveller bars adjacent the opposite ends of the stacks and having latches at their opposite extremities, means for simultaneously reciprocating the traveller bars, and means for arranging the sign stacks whereby the foremost sign of one stack and the rearmost sign of the other stack will be within the path of movement of a latch on the adjacent traveller bar, including shoes engaging the endmost signs of each stack and arranged to compress the signs in each stack and guide the transferred signs in their passage from one stack to the other.

5. In a device of the character described, projecting mechanism including an electric lamp, and a lens, a plurality of groups of signs arranged in a pair of stacks positioned one on each side of a projecting mechanism, metal bridge contacts carried by the foremost signs of each group, means controlled by a bridge contact for transferring the foremost sign of either stack into position for projection, and then onto the other stack, includ-

ing a motor means for intermittently energizing the motor to transfer the foremost sign of one stack into position for projection, and means for extinguishing said lamp during the operation of the motor.

6. In a device of the character described, projecting mechanism including an electric lamp, and a lens a plurality of groups of signs arranged in a pair of stacks positioned one on each side of a projecting mechanism, metal bridge contacts carried by the foremost signs of each group, means controlled by a bridge contact for transferring the foremost sign of either stack into position for projection, and then onto the other stack, including a motor, means for intermittently energizing the motor to transfer the foremost sign of one stack into position for projection, and means set in motion by the energized motor for deenergizing the motor after such movement of the foremost sign.

7. In a device of the character described, projecting mechanism including an electric lamp, and a lens, a plurality of groups of signs arranged in a pair of stacks positioned one on each side of the projecting mechanism, metal bridge contacts carried by the foremost signs of each group, means for transferring the foremost sign of either stack into position for projection, and then onto the other stack, including a motor, means for intermittently energizing the motor to transfer the foremost sign of one stack into position for projection, means for extinguishing said lamp during the operation of the motor, means for automatically deenergizing the motor after such movement of the foremost sign, and means for preventing the operation of said deenergizing means until the foremost sign of a desired group has reached the position of the foremost sign of one of the stacks.

8. In a device of the character described, a frame, projecting mechanism arranged substantially centrally of the frame, a pair of stacks of signs arranged at the sides of the projecting mechanism, means for simultaneously transferring the foremost sign of one stack and the rearmost sign of the other stack onto the opposite stacks to maintain constant the number of signs in each stack, and means for guiding and positioning the transferred signs, including a pair of shoes pivotally mounted adjacent the ends of the stacks having inwardly extending inclined edges against one of which the transferred signs engage as they approach the receiving stack, and springs urging the shoes into substantially constant engagement with the stacks.

9. In a device of the character described, a frame, projecting mechanism arranged substantially centrally of the frame, a pair of stacks of signs arranged at the sides of the projecting mechanism, means for simultaneously transferring the foremost sign of

one stack and the rearmost sign of the other stack onto the opposite stacks to maintain constant the number of signs in each stack, and means for guiding and positioning the transferred signs, including a pair of shoes pivotally mounted adjacent the ends of the stacks and having inwardly extending inclined edges, means for positioning the shoes whereby the shoes adjacent the receiving stacks are closer to the signs than the shoes adjacent the stacks from which the signs are transferred, and means for reversing the positions of the shoes relatively to the stacks.

In witness whereof, I hereunto set my hand.

FRANK FRYE.
